UNITED STATES PATENT OFFICE.

WHITFIELD H. EDWARDS, OF OAKDALE, LOUISIANA.

RAIL-FASTENER FOR RAILWAYS.

1,206,098.

Specification of Letters Patent. Patented Nov. 28, 1916.

Application filed April 27, 1915. Serial No. 24,206.

To all whom it may concern:

Be it known that I, WHITFIELD H. EDWARDS, a citizen of the United States, residing at Oakdale, in the parish of Allen and State of Louisiana, have invented certain new and useful Improvements in Rail-Fasteners for Railways, of which the following is a specification.

This invention relates to new and useful improvements in a rail fastener for rail-ways.

The object of the invention is to provide means whereby the abutting ends of rail-way rails may be secured together and also secured to the ties so as to form secure joints.

Another object of the invention resides in the provision of a device of the character described whereby the rails may be easily secured upon the ties.

With the above and other objects in view, the invention has particular relation to certain novel features of construction, arrangement of parts and use, an example of which is given in this specification and illustrated in the accompanying drawings, wherein:

Figure 1, shows a plan view of a section of railway track showing the rails secured to the ties. Fig. 2, shows a side elevation thereof. Figs. 3, 4, and 5, show, respectively, edge, plan and end views of the fish-plate employed. Fig. 6, shows a fragmentary isometric view of one form of tie employed. Fig. 7, shows an isometric view 35 of a wedge used in applying the device. Figs. 8 and 9, show, respectively, side and end views of the form of bolts and lock nut employed. Figs. 10 and 11, show, respectively, sectional views taken on the lines 40 *a—a*, and *b—b*, of Fig. 1. Fig. 12, shows a fragmentary view, partially in section, of the rail-brace. Fig. 13, illustrates the method of applying the rail to the tie. Fig. 14, shows an enlarged side elevation of the fish-plate, as applied to the rail and tie, and, 45 Figs. 15 and 16, show, respectively, sectional and plan views of the rail-plate.

Referring now more particularly to the drawings, wherein like numerals of reference designate similar parts in each of the figures, the numerals 1, 1, refer to the rails of a track, and the numerals 2, 2, designate contiguous rails forming a continuation of said track, the abutting ends of the corresponding rails 1 and 2, being secured together by the improved method, as will be

hereinafter set forth. These rails are mounted upon the ties 3, which are preferably formed of I beams, as shown.

The abutting ends of the corresponding 60 rails, are secured together by means of the inner and outer fish-plates 4 and 5, formed of angle-irons, the upstanding portion of which rests against the inner and outer sides of the rail-web, and are secured to the rail 65 by means of a plurality of bolts, as 6, which pass through the upstanding portions of said fish-plates and through said web. These bolts are secured in position by an improved form of lock-nut 7, as shown in 70 Figs. 8 and 9, but it is not thought necessary to describe the same in detail, as it is fully described in the patent issued to me thereon by the United States Patent Office. The underside of the horizontal portion of 75 each fish-plate, is shaped to conform to the rail-base and extends beyond said base and rests upon the tie, to which it is secured by means of the vertically extending bolts 8, which extend through the fish-plate and the 80 tie flanges, as shown in Fig. 14, and the underside of said flanges being tapered, a supplemental wedge-shaped washer 9, is provided for each of the bolts 8, which is inserted between the bolt head and the underside of the tie flange, to compensate for the taper of said underside.

The respective ends of the fish-plate rest upon the corresponding proximate ties 3, 3, Fig. 1, and are held against spreading by 90 means of the shoulders 10, 10, which are integral with the ties and projecting laterally from each fish-plate, at opposite ends, are the flanges 11, 11, which fit into undercut grooves, in the shoulders 10, 10, and reinforce the bolts 8.

The rails are secured intermediate the joints to the ties in the manner illustrated in Figs. 11 and 12, wherein the numerals 12, 12, refer to shoulders which are integral 100 with the tie and have undercut grooves to receive the adjacent flanges of the rails and on the opposite sides of said respective rails and integral with the ties are the shoulders 13, 13, having undercut grooves, in which the adjacent ends of the braces 14, 14, fit. These braces are bolted to the ties and fit over the corresponding rail-flanges and rest against the rail-webs, opposing the shoulders 12, 12. From an inspection of Fig. 1, it 110, will be observed that the shoulders 12 and 13, are alternatively arranged, with respect

to the rails, on the alternate ties; that is said shoulders are arranged on the opposite side of the rail, on one tie, from that of the one next to it, so as to brace the rail equally on both sides.

I have shown only one form of this device, but it is obvious that the mechanical structure thereof may be varied without departing from the principle of the invention, 10 and I hereby reserve the right to make such structural changes, as may be found necessary, so long as I keep within the scope of the appended claims.

What I claim is:

15. 1. In a device of the character described, including the combination with railway ties, of rails mounted thereon whose ends abut, upstanding projections integral with the ties on the opposite sides of the rails, said projections having undercut grooves, fish plates arranged on opposite sides of the abutting ends of said rails adapted to span from one tie to another, whose outer edges rest in said grooves and are secured to said tie and 25 whose inner edges are upturned and rest

against the corresponding side of the rail web.

2. In a device of the character described the combination with railway ties formed of I-beams of rails mounted thereon having 30 abutting ends, upstanding projections integral with the ties and on opposite sides of the rail and spaced therefrom, whose inner sides have undercut grooves, fish plates spanning from one tie to the other arranged 35 on opposite sides of said abutting ends, whose outer edges rest in said grooves and are bolted to the web of said I-beams and whose inner edges are formed to correspond to the contour of and rest against the adjacent sides of the rails and means for securing said plates to the rail webs.

In testimony whereof I have signed my name to this specification in the presence of two subscribing witnesses.

WHITFIELD H. EDWARDS.
